REVERSE CIRCULATION ROTARY PACKER

Bruno R. Schabarum, Midland, Tex., assignor to
 Carl E. King Drilling Company, Midland, Tex.,
 a corporation of Delaware

Application September 19, 1947, Serial No. 774,910

5 Claims. (Cl. 255—24)

1

This invention relates to a circulation reversing tool for use in rotary drilling and particularly to a reverse circulation rotary packer whereby circulation of drilling fluid through a well may be transferred from the interior of the drill pipe to the exterior thereof at spaced points along its length above the lower end thereof without altering the conventional circulation connections at the surface.

In conventional rotary drilling the drilling fluid is normally circulated in the well by pumping it through the interior of the hollow drill pipe from which it discharges through suitable openings in the bit and thence flows upwardly through the annular space between the well bore and casing and the drill pipe, returning to the surface through the annular space in the surface casing and discharging therefrom for return to the interior of the drill pipe by the pump in completing the cycle.

In many types of drilling operations, it is found desirable to reverse the ordinary direction of flow of the drilling fluid and cause the fluid to flow down the annular space and back through the interior of the drill pipe to the surface. Heretofore this reversal of flow has been accomplished by providing special cross-over or reversing connections at the top of the well. Such cross-over or reversing connections normally require considerable equipment, as well as additional time and effort on the part of the drilling crew to accomplish the desired reversal in circulation.

The principal object of the device, in accordance with this invention, is to effect the desired reversal in direction of circulation of the drilling fluid in a relatively simple manner, which eliminates use of special reversing connections at the surface and additional labor or attention on the part of the drilling crew.

An important object is the provision of a circulation reversing tool of very simple design for insertion in the drilling string at any desired point at which the reversal in flow is to be made.

A more specific object is the provision of a tool having a passageway extending from each end of the interior thereof to the exterior of the tool adjacent the opposite end thereof and a compressible packing element about the exterior of the tool between the outlets of the passageways for packing off between the tool and the surrounding casing, whereby the fluid is transferred from the interior of the drill pipe to the exterior thereof and after returning through the interior of the drill pipe to the vicinity of the

2

tool is again transferred to the exterior of the tool at a point above the point of first transfer for completing its circuit to the exit of the well through the conventional connection.

Other and more specific objects and advantages of this invention will be apparent from the following detailed description when read in conjunction with the accompanying drawings which illustrate useful embodiments in accordance with this invention.

In the drawings:

Fig. 1 is a longitudinal sectional view through the tool in accordance with this invention shown disposed inside a well casing;

Fig. 2 is a diagrammatic view of a well showing the tool inserted in a drilling string within the well;

Fig. 3 is a detail showing another embodiment of the packing element forming a part of the tool in accordance with this invention; and

Fig. 4 is a cross-sectional detail taken along line 4—4 of Fig. 3.

Referring to the drawings, and to Fig. 1 particularly, the tool comprises a cylindrical body 10 having a hollow internally threaded box 11 at one end, which is of conventional form for the reception of the usual tool joint pin, and a hollow externally threaded pin 13 at the opposite end, also of conventional form, for insertion in the box of the drilling string into which the tool is inserted. A passageway 14 communicates with the interior of box 11 and extends at an angle through the major portion of the length of the body, communicating with the exterior thereof through a port 15 adjacent pin 13. A second passageway 16 communicates at one end with the interior of pin 13 and extends in the opposite direction through the body, generally parallel to passageway 14, communicating with the exterior of the body through a port 17 adjacent box 11.

Mounted on the exterior of the body between ports 15 and 17 is a sleeve packer 18 constructed of any suitable flexible or resilient material, such as natural or synthetic rubber or the like. Packer 18 is tightly mounted on the exterior of body 10 either by vulcanizing directly to the body metal or by any other suitable or conventional means. The lower end of the packer may be provided with a flexible annular lip 19 which is adapted to be expanded by fluid pressure into compressive relationship with the wall of a surrounding casing 20 in which the tool is normally run. The thickness of the packer is such as to make a relatively close sliding fit within casing 20, or other pipe into which

the tool is inserted.

the tool may be run, so that when subjected to compression by fluid pressure, the packer will expand into fluid-tight engagement with the surrounding casing or pipe.

The passageways 14 and 16 are inclined at a slight angle to the longitudinal axis of the body of the tool. This permits making the passageways of greater diameter, thereby permitting passage of larger particles of cuttings than would otherwise be the case. It also obviates any sharp angle changes in direction of the flow of the drilling mud. These features minimize the likelihood of stoppages. When employing a flow such as is described herein, one of the advantages of the apparatus is that larger sizes of the rock specimens are brought to the surface than in the case of conventional operations or of other systems of reverse flow. If the holes in the drill bits are not sufficiently large to permit passage of the larger cuttings, these can be enlarged. In conventional operation in which the drilling mud is returned along the casing, the conventional drilling collars employed in such operations grind the cuttings to rather fine particles. This does not occur when the present device is used, because the cuttings are returned through the drill pipe until within a few feet of the surface. The larger pieces of cuttings have the advantage of simplifying geological examination thereof.

The above described tool is employed in the following manner in connection with rotary drilling operations, reference being had to Fig. 2: The tool is preferably inserted in a drilling string 21, just below the conventional Kelly joint 22 so that during operation, irrespective of the increasing or decreasing length of the drilling string employed, the tool will always be positioned within the usual surface casing 20. The upper end of Kelly joint 22 is connected in the conventional manner to the usual swivel 23 through which drilling mud is introduced by the mud pumps (not shown) through a goose neck 24. The Kelly joint extends through the usual rotary table 25 shown mounted on a derrick floor 26 above the mouth of surface casing 20, the latter being provided adjacent its upper end with the usual outlet pipe 27 from which the mud fluid returning from the well is discharged in the usual manner to the mud ditches (not shown) from which, after the usual screening or settling operations, the mud is picked up by the mud pumps and returned to the interior of the drilling string. With the tool inserted in the drilling string as above described, the mud entering the interior of the drilling string in the usual manner will flow downwardly through the interior thereof and through passageway 14 emerging therefrom at port 15 below packer 18 and will then travel downwardly through the annular space between the exterior of the drilling string and the casing to the lower end of the drilling string, where it will again enter the interior of the drill pipe, through the usual bit or other openings in the pipe string, and flow upwardly therein until the fluid reaches the lower end of the tool. There it will enter passageway 16 which will again divert the fluid to the exterior of the drill pipe through port 17 above the upper end of packer 18. The fluid will then return to the upper end of the well in the conventional path, namely, through the annular space between the drilling string and casing 20, from which the fluid will be discharged in the usual manner through the outlet pipe 27 and into the mud ditches, completing the cycle. The pressure of the fluid

against the ends of packer 18 will compress the latter longitudinally and expand it radially into sealing engagement with the inner wall of casing 20 with the result that the bodies of fluid above and below the packer will be completely segregated and the fluid will, therefore, follow the circuit above described. The drilling string may, of course, be rotated in the usual manner, by means of the usual connection of the rotary table to the Kelly joint, and with the arrangement described there will be no interference with the rotation of the drilling string by the circulation reversing tool. Packer 18 will act as a rotating bushing which is in constant sealing contact with the wall of casing 20. With the described arrangement it will be seen that the necessity for complicated or elaborate cross-over connections and requisite valves at the top of the well are completely eliminated and drilling and handling of drilling fluid are conducted in the conventional manner.

Although the tool may be inserted in the drilling string at any desirable point within the casing, it is normally preferable to locate it, as described, immediately below the Kelly joint. This has the advantage that since it is always necessary to pull the Kelly joint out of the well when adding or removing sections of the drill pipe, the tool and packer 18 will, in each instance, be brought out of the well under the view of the drilling crew where any damage due to wear or other causes to the tool or packer may immediately become evident to the operators and necessary repairs or changes made. Also the casing will form a relatively smooth surface for the rotating packer.

It will be understood that the form of packer 18 may be varied considerably and may be of any suitable construction which will be readily apparent to those skilled in this art.

Figs. 3 and 4 illustrate details of such another form of packer which may be successfully used with the tool of this invention. In this embodiment body 10 is undercut successively at 28 and 29, the undercut portions being provided with longitudinal spline grooves 30 and 31, respectively. Packer 18 is slidable over the undercut portions of body 10 from the lower end thereof and has imbedded in the upper and lower inner ends thereof spaced metal rings 32 and 33 respectively, which encircle the undercut portions of body 10. Rings 32 and 33 are provided with tongues 34 and 35, respectively, which project radially therefrom into spline grooves 30 and 31, respectively, to thereby permit relative longitudinal movement between packer 18 and body 10 while preventing relative rotational movement between these members. A section of undercut portion 29 is externally threaded at 36 to receive a jam nut 37 which when screwed on threaded section 36 is adapted to adjustably urge ring 33 toward ring 32 and thereby compress packer 18. This adjustment is provided to permit take-up for wear on the packer. Set screws 38 extend radially through the body of nut 37 into engagement with undercut portion 29 for locking the nut in the desired adjusted position. In all other respects body 10 is identical with the embodiment previously described.

It will be understood that various other changes and alterations may be made in the details of the device in accordance with this invention without departing from the scope of the appended claims but within the spirit of this invention.

What I claim and desire to secure by Letters Patent is:

1. A circulation reversing rotary packer for use in rotary drilling, comprising, an elongated body for insertion in a hollow pipe string, means on the opposite ends of said body for connecting it into said string, a pair of separate fluid passageways extending in opposite directions through said body, each of said passageways connecting one end of said body with the side thereof at a point adjacent the opposite end of said body, said passageways being inclined at an angle to its longitudinal axis, and a compressible packing element non-rotatably mounted on said body and surrounding said body intermediate the outer ends of said passageways adapted to form a fluid-tight seal therebetween and between the exterior of said body and a surrounding casing.

2. A circulation reversing rotary packer for use in rotary drilling, comprising, a cylindrical body having a hollow internally threaded box portion at one end and a hollow externally threaded pin portion at the opposite end for connecting said body to adjacent sections of a hollow pipe string, a passageway communicating with the interior of said box member and extending generally longitudinally through said body to the exterior thereof at a point on the side thereof adjacent said pin member, a second passageway communicating with the interior of said pin member and extending generally longitudinally through said body to the exterior thereof at a point on the side thereof adjacent said box member, said passageways being inclined at an angle to the longitudinal axis of said body, and a compressible packing element non-rotatably mounted on said body and surrounding said body intermediate the outer ends of said passageways adapted to form a fluid-tight seal therebetween and between the exterior of said body and a surrounding casing.

3. A circulation reversing rotary packer for use in rotary drilling, comprising, an elongated body for insertion in a hollow pipe string, a pair of fluid passageways extending in opposite directions through said body, each of said passageways connecting one end of said body with the side thereof at a point adjacent the opposite end of said body, and a compressible packing element non-rotatably mounted on said body and surrounding said body intermediate the outer ends of said passageways adapted to form a fluid-tight seal therebetween and between the exterior of said body and a surrounding casing, said packing element comprising a flexible, resilient sleeve member slideable on said body, and means cooperating between said body and the ends of said sleeve member for longitudinally compressing said sleeve member to effect radial expansion thereof.

4. A circulation reversing rotary packer for use in rotary drilling, comprising, an elongated cylindrical body, hollow connections at its opposite ends for connecting said body to adjacent sections of a hollow pipe string, a first single passageway communicating at one end with the interior of one of said hollow connections and extending through said body at an angle to the longitudinal axis thereof to emergence of its other end at one side of said body adjacent the other of said hollow connections, a second single passageway communicating with said other of said hollow connections and extending through said body in parallel spaced relation to said first passageway to emergence of its other end at the opposite side of said body adjacent the first said hollow connection, and a compressible packing element non-rotatably mounted on said body surrounding said body intermediate the outer ends of said passageways adapted to form a fluid-tight seal therebetween and between the exterior of said body and a surrounding casing.

5. A circulation reversing rotary packer for use in rotary drilling, comprising, an elongated cylindrical body having hollow connections at its opposite ends for connecting said body to adjacent sections of a hollow pipe string, a pair of spaced parallel fluid passageways extending in opposite directions through said body at an angle to its longitudinal axis, each of said passageways connecting one of said hollow connection members with the exterior of said body at a point adjacent the opposite end thereof, a resilient packing sleeve surrounding said body between the outer ends of said passageways, said sleeve being radially expandible by longitudinal compression thereof, longitudinally splined connections between the opposite ends of said sleeve and said body providing limited relative longitudinal movement between the ends of said sleeve along said body while preventing relative rotational movement between said sleeve and said body, and thrust means carried by said body and engageable with the lower end of said sleeve to longitudinally compress said sleeve.
